UNITED STATES PATENT OFFICE.

JAMES PATERSON, OF LEYTONSTONE, ENGLAND.

IMPROVEMENT IN APPARATUS FOR CAPSULING BOTTLES.

Specification forming part of Letters Patent No. 148,976, dated March 24, 1874; application filed March 9, 1874.

CASE A.

To all whom it may concern:

Be it known that I, JAMES PATERSON, of Leytonstone, in the county of Essex, England, have invented certain Improvements in Capsuling Bottles and other Vessels, of which the following is a specification:

My invention relates to an improvement in the mode of applying metallic capsules to bottles for which Letters Patent No. 121,407 were granted to William Betts, as my assignee, on the 28th day of November, 1871; and the object of my invention is to fix the capsules more expeditiously and effectually than heretofore, by operating the elastic diaphragm described in the said patent by simple mechanical appliances, instead of by the pressure of a surrounding fluid.

In the accompanying drawing, Figure 1 is a front elevation of my improved capsuling apparatus with the cover-plate removed; Fig. 2, a sectional elevation of the same, and Fig. 3 a detached view of the elastic block or diaphragm.

The elastic block A is, in the present instance, of a cruciform shape, and has a central aperture or chamber, x, for the reception of the neck of the bottle or other vessel, and of the metallic capsule to be fixed to the same by pressure. The said block is fitted into radial grooves formed for its reception on the projecting face of the standard B of the machine, and is held therein by the face-plate C. A dog or slide, D, is adapted to each of the radial grooves of the standard, and is caused to bear against the elastic block, so that, when all of the dogs are forced inward simultaneously, their combined pressure will uniformly contract the central opening x of the elastic block, and cause the latter to gripe and compress the capsule around the neck of the bottle.

Various mechanical devices, such as eccen-

trics, cranks, and screws, may be used for operating the sliding dogs; but I prefer to employ a ring, E, arranged to be turned upon the exterior of the circular portion of the standard by an arm or lever, F, and having internal cam-like inclines a opposite each of the sliding dogs. On turning the said ring in the direction of the arrow, the whole of the dogs will be forced inward simultaneously, and will compress the rubber block around the capsule, and, on returning the ring to its original position, the inherent elasticity of the rubber will force the slides back against the ring, and the apparatus will then be ready for a repetition of the operation.

I do not desire to confine myself to a cruciform block, A, nor to the use of four radial slides, as the said block may have a polygonal or a curved exterior, and any suitable number of slides may be used, so shaped at their inner ends as to conform to the exterior of the elastic block.

I claim as my invention—

1. In a machine for applying capsules to bottles and other vessels, the combination, substantially as described, of an elastic tubular block or diaphragm with sliding dogs D, arranged radially around the same, for the purpose specified.

2. The combination, substantially as described, of the elastic block or diaphragm A, the radially-sliding dogs D, and the cam-ring E.

In witness whereof I have signed my name to this specification in the presence of two subscribing witnesses.

JAMES PATERSON.
